UNITED STATES PATENT OFFICE.

CHARLES C. ALGEO, OF PHILADELPHIA, PENNSYLVANIA, ASSIGNOR OF
ONE-HALF TO W. IRVING STEEL, OF SAME PLACE.

SASH-FASTENER.

SPECIFICATION forming part of Letters Patent No. 521,691, dated June 19, 1894.

Application filed November 20, 1893. Serial No. 491,416. (No model.)

To all whom it may concern:

Be it known that I, CHARLES C. ALGEO, a citizen of the United States, residing at Philadelphia, Pennsylvania, have invented certain 5 Improvements in Sash-Fasteners, of which the following is a specification.

The object of my invention is to provide a simple, neat and effective device for locking together the upper and lower sashes of a window, and this object I attain in the manner hereinafter set forth, reference being had to the accompanying drawings, in which—

Figure 1, is a perspective view of parts of the upper and lower sashes of a window, and 15 of the frame in which they are guided, illustrating my improved sash lock. Fig. 2, is a transverse section of parts of the sashes and the locking device applied thereto; and Fig. 3, is a similar view showing the parts in different relation to each other.

A represents part of the frame of the upper sash and B part of the frame of the lower sash, and D represents part of the framework in which the sashes are guided in the usual 25 way. Let into the face of the side rail of the upper sash is a plate F for the locking bolt G, said plate having an inclined bolt guide a with transverse pin b adapted to a slot d in the bolt and serving to limit the forward movement of the latter, as shown in Fig. 2. The plate F has, above the inclined bolt guide, a recess f for the reception of an inclined tongue g projecting upwardly from the forward end of the bolt G.

30 The top of the lower sash B is provided with a catch plate h which, when the sashes are fully closed, as shown in Fig. 2, is overlapped by the projecting end of the bolt G so as to effectually prevent either the raising of 35 the lower sash or the lowering of the upper sash until the bolt G has first been pushed backward and its forward end is free from engagement with the plate.

When the upper sash is being raised or the 45 lower sash is being lowered, the outer edge of the meeting rail of said lower sash acts first upon the inclined finger g of the locking bolt

and then upon the inclined or beveled forward end of the bolt itself, as shown in Fig. 3, so as to force back said bolt, the latter moving forward into locking position as soon as the sashes are close together and the catch plate h has passed below the bottom of the bolt.

The forward end of the bolt G is beveled on the underside as shown at i so as to provide a 50 flat or horizontal bearing portion for engagement with the catch plate h and thereby overcome any tendency which vertical pressure might otherwise have to cause the bolt to slide upward and inward and thus release the 55 sashes.

Instead of relying wholly upon gravity to effect the projection of the locking bolt this action may be reinforced by a spring interposed behind the bolt as shown for instance 60 by dotted lines in Fig. 2, or in some cases the bolt G may be arranged horizontally and the spring may be wholly relied upon to effect the projection of the same.

If it is desired to lock the sashes when the 65 same are partly opened or to lock them in different positions the upper sash may have disposed throughout the length of the side rail of the sash a series of plates F each with locking bolt G.

Having thus described my invention, I 70 claim and desire to secure by Letters Patent—

The combination in a sash lock, of the casting having an upwardly inclined bolt guide, a recess above the bolt guide, a bolt adapted 75 to the guide and having a beveled tongue adapted to the recess, and so proportioned that the lower sash as it descends will push the bolt back by the tongue and said tongue acting as a finger push to release the sash, substantially as described.

In testimony whereof I have signed my name to this specification in the presence of two subscribing witnesses.

CHARLES C. ALGEO.
